United States Patent

Des. 236,540
Patented Aug. 26, 1975

236,540

PORTABLE RADIO

John T. Houlihan, Fayetteville, N.Y., assignor to General
Electric Company, Syracuse, N.Y.

Filed Mar. 25, 1974, Ser. No. 454,089

Term of patent 14 years

Int. Cl. D14—03

U.S. Cl. D56—4 B

FIG.1

FIG.2

FIG.3

FIG.4

FIG.5

FIG.6

FIG. 1 is a front elevational view of a portable radio showing my new design;

FIG. 2 is a rear elevational view;

FIG. 3 is a right side elevational view;

FIG. 4 is a left side elevational view;

FIG. 5 is a top plan view; and

FIG. 6 is a bottom plan view.

I claim:

The ornamental design for a portable radio, substantially as shown.
